G. E. OAKLEY

DOOR MOTOR CONTROL

Filed Sept. 14, 1920

UNITED STATES PATENT OFFICE.

GEORGE E. OAKLEY, OF ALBANY, NEW YORK, ASSIGNOR TO CONSOLIDATED CAR-HEATING COMPANY, OF ALBANY, NEW YORK, A CORPORATION OF WEST VIRGINIA.

DOOR-MOTOR CONTROL.

Application filed September 14, 1920. Serial No. 410,206.

To all whom it may concern:

Be it known that I, GEORGE E. OAKLEY, a citizen of the United States, residing at Albany, in the county of Albany and State 5 of New York, have invented certain new and useful Improvements in Door-Motor Controls, the following being a full, clear, and exact disclosure of the one form of my invention which I at present deem preferable.

- 10 For a detailed description of the present form of my invention, reference may be had to the following specification and to the accompanying drawings forming a part thereof.
- 15 My invention relates to a pneumatic reversing door engine which is controlled manually from a distant point for its usual operations and automatically controlled in the event of the door in its closing movement 20 encountering an obstruction.

Referring to the drawing, D represents a door of the sliding type having on its forward edge a "shoe" S such as is commonly known in the art and consisting of a bar or strip that is mounted on the door and will yield inwardly against the door in case it encounters some object such as a car passenger when the door is closing. In my present arrangement the shoe S is permanently grounded and when pressed inwardly 25 will engage an insulated contact 10 on the door and connect it to ground. The contact 10 is connected as is customary to a brush 16 which is fast on the door and travels in contact with a stationary conductor 17, as the door moves to and fro.

The conductor 17 is connected to a contact point 8 which is connected to a similar contact 9 whenever there is air pressure on a 30 small cylinder and piston 1 which forces a contact plate outward against the points 8 and 9. The same cylinder 1 is in communication with door-closing cylinder C² of the reversible door-operating engine so 35 that, whenever the door is being closed by pressure in the cylinder C², the contact points 8 and 9 are electrically connected, but are disconnected at all other times. As a result, the shoe S, contact 10, brush 16 and 40 the connections therefrom to point 8 are dead and functionless except when the door is being closed, and it is only in its closing

action that the door is liable to encounter an obstruction.

A represents the push-button switches for 55 manual control of the door. For closing, the top button will be pressed downward to connect points 2 and 3, but for opening the lower button will be pressed upward to connect points 13 and 14 the switch standing 60 at all other times in the intermediate position. The switch stem is provided on one side with a spring a which acts to return it to its intermediate position when it is pushed upward to connect points 13 and 14; 65 but it has no spring on the other side so that when pressed to connect points 2 and 3, the contact plate will remain in contact therewith until pushed back to its intermediate position.

C is a magnet which initiates the door-closing action of the engine, and O a similar magnet for its door-opening action. These magnets serve to control valves of any desired type (conventionally illustrated) 75 which admit air pressure to the cylinders C² and O² that throw the valve-bar 2 of the engine to left or to right to give the engine its corresponding reverse movements to either close 80 or open the door. Such reversers comprising magnets and valve-bar cylinders are well known (see U. S. Patent 1,479,386, dated Jan. 1, 1924) and require no further description, except to point out that the 85 opening cylinder O² is larger than the closing cylinder C², so that if air is admitted to both at the same time, O² will overpower C² and move the valve-bar to give the engine its door-opening movement in spite 90 of the pressure existing in the closing cylinder C². The purpose of this is to give O² the power, under control of the door shoe, to produce the opening action of the 95 engine without the necessity of first releasing the pressure in the closing cylinder C².

This principle of a master door-opening agency that will overpower the door-closing agency in the emergency of an obstruction being encountered by the door may be embodied in various different ways. The advantage of it is that the closing agent remains in active condition, although tem-

porarily overpowered, and resumes its duty as soon as the emergency is past and the overmastering force removed.

There is also provided at the door D contact points 4 and 5 which are separated whenever the door is fully closed, but are in contact with each other at all other times. These contacts are in the circuit of closing-magnet C and serve to disable that magnet 10 when the door is closed, the control being then vested in the opening-magnet O. Moreover, when switch A is pushed into contact with points 2 and 3, thereby energizing closing-magnet C, it simultaneously energizes a 15 relay R whose armature 12 then switches the circuit of opening-magnet O from ground to a battery B¹. Since switch A remains in the position to which it has been pushed, both C and R will remain energized 20 during the door-closing operation, at the end of which they are released by the opening of contacts 4 and 5. The connection of the battery B¹ to magnet O during this 25 period, will permit of a flow of current from said battery to magnet O in the event of the door-shoe S being forced by an obstruction into contact with point 10. The points 8 and 9 which are in that branch of the opening circuit which leads to the door-shoe are closed at this time by the pressure in the closing-cylinder C³.

For the usual normal operation the only thing necessary, for opening the door when it is closed, is the momentary pushing up 35 of button-switch against points 13 and 14. That will close a circuit from battery B, to points 13, 14, to magnet O, to relay armature 12 to ground. This is the usual manually controlled opening circuit for 40 magnet O and is supplied with current from battery B. Thereupon magnet O will actuate its valve to admit air to valve cylinder O² which will shift the engine valves to cause the door-opening movement. That 45 will require but a momentary action of the electrical parts and the manual switch will, when released, return automatically to its intermediate position. For closing the door when it is open, the button-switch is pressed 50 down in the opposite direction against points 2 and 3, and then it does not snap back to its intermediate position but remains in contact with 2 and 3. This establishes a circuit from battery B, to points 2 and 3, to 55 points 4 and 5 which are now closed, the door being open, to closing-magnet C to ground and also to relay magnet R and ground. Since the button-switch does not in this case snap back to its intermediate 60 position, but remains where it has been pushed, in contact with 2 and 3, the closing circuit just traced is maintained while the door is closing, being finally opened at contacts 4 and 5 when the door is fully 65 closed. This affords the opportunity for

the emergency energizing of opening-magnet O, in case the door meets an obstruction during the period when closing magnet C is energized. But since the cylinder O² controlled by O is larger 70 than the cylinder C² controlled by C, the latter will be overpowered by O². The circuit for this master action of O² will be from battery B¹ to 12 (now held attached by R) to magnet O, to points 8 and 9 (now closed by air pressure in C³) to bar 17, brush 16, point 10, shoe S and to ground. This circuit is supplied with current from battery B¹ by the battery connection which 75 establishes and includes the branch leading to the door shoe. Thus during the normal door-closing operation, the emergency, master action of the door-closing means is always possible. The effect of the master action is to reverse the engine by shifting 80 the air pressure from cylinder C³ to cylinder O³; the release of pressure in C³ opens contact points 8 and 9, thereby breaking the aforesaid emergency circuit of magnet O, releasing the pressure in master cylinder O² 85 and permitting the cylinder C² to resume its control of the engine valves. Thereupon the engine again reverses to door-closing movement. If the obstruction is not removed the emergency action will be repeated 90 and the re-reversing will be continued so long as the obstruction is present. Ultimately the closing operation will prevail and the door will stand in its normal closed position, its final movement breaking the 100 connection between points 4 and 5 which opens the circuits of C and R independently of its button-switch. It will be therefore manifest that while the usual manual control of the door is provided for, there exists 105 during the closing operation an opportunity for the temporary, emergency action of the door-opening means which include the overpowering agency, viz the cylinder O², in the present specific apparatus.

What I claim as new and desire to secure by Letters Patent is:

1. A door control system comprising door closing control means, door opening control means capable of dominating the door closing control means, and emergency means for causing the door opening control means to temporarily dominate the door closing control means.

2. A door control system comprising a door engine, reversing valves therefor, two electro-magnetically controlled valve shifters, one of which is capable of dominating the other, and an emergency device controlling the dominating valve shifter.

3. A door control system comprising a door engine, reversing valves therefor, two electro-magnetically controlled valve shifters, one of which is capable of dominating the other, manual switches controlling both

valve shifters, and an emergency device also controlling the dominating valve shifter.

4. A door control system comprising a door engine, reversing valves therefor, two electro-magnetically controlled valve shifters, one of which is capable of dominating the other, manual switches controlling the respective valve shifters, a switch in the control circuit of the door opening valve shifter, means in the control circuit of the door closing valve shifter controlling said switch, and an emergency device controlling the dominating valve shifter.

5. A door control system comprising a door engine, reversing valves therefor, two electro-magnetically controlled valve shifters, one of which is capable of dominating the other, manual switches controlling both valve shifters, means for maintaining the door opening valve shifter in operative condition during the door closing period, and an emergency device also controlling the dominating valve shifter.

6. A door control system comprising a door engine, reversing valves therefor, pneumatically actuated valve shifters for said valves, one of which is capable of dominating the other, electro-magnetic devices controlling said shifters, manual switches controlling the circuits to said electro-magnetic devices, and an emergency device controlling the circuit to the magnetic device which governs the dominating valve shifter.

7. A door closing system comprising a door engine, reversing valves therefor, two electro-magnetically controlled valve shifters, one of which is capable of dominating the other, a switch controlling the control circuit of the dominating valve shifter, said switch being in the control circuit of the other valve shifter, and a travelling emergency switch also controlling the circuit to the dominating valve shifter.

8. A door control system comprising a reversing door engine, door opening and closing valves therefor, a valve shifter for the door closing valve, a controlling circuit therefor, a switch for maintaining said circuit during the door closing period, a valve shifter for the door opening valve capable of dominating the first mentioned shifter, a circuit therefor controlled by the door closing valve shifter, and an emergency switch in said controlled circuit.

9. A door control system comprising a door engine having valves to secure door opening and door closing functions, an electrically controlled valve shifter for the door closing valve, an electrically controlled valve shifter for the door opening valve, two battery connections in the control circuit of said last mentioned valve shifter, a manual switch controlling said circuit under one of the two battery connections, an emergency switch controlling the circuit under its other

battery connection, and a switch in the control circuit of the first mentioned valve shifter for establishing the last mentioned battery connection.

10. A door control system comprising a door engine, reversing valves therefor, valve shifters controlling the respective valves, the one controlling the opening valve shifter being capable of dominating the other, magnets controlling the respective shifters, a circuit for the magnet which controls the door closing shifter, a manual circuit-maintaining switch for said closing circuit, a circuit for the magnet which controls the door opening shifter, a momentary closing switch for said last mentioned circuit, a branch from said last mentioned circuit including an emergency switch, and a battery shifting switch for the last mentioned circuit controlled by the first mentioned circuit.

11. A door control system comprising a door engine, reversing valves therefor, valve shifters controlling the respective valves, the one which controls the opening valve shifter being capable of dominating the other, a circuit for the magnet which controls the door opening shifter, manual switches for the respective circuits, an emergency branch connected with the circuit which controls the door opening shifter, and a battery shifter for the last mentioned circuit controlled by the first mentioned circuit.

12. A door control system comprising a door engine, reversing valves therefor, valve shifters controlling the respective valves, the one which controls the opening valve shifter being capable of dominating the other, a circuit for the magnet which controls the door opening shifter, manual switches for the respective circuits, an emergency branch connected with the circuit which controls the door opening shifter, a travelling emergency switch controlling said branch, and a battery connection for the opening circuit controlled by the closing circuit.

13. A door control system comprising a door engine, reversing valves therefor, valve shifters controlling the respective valves, the one which controls the opening valve shifter being capable of dominating the other, a circuit for the magnet which controls the door opening shifter, manual switches for the respective circuits, an emergency branch connected with the circuit which controls the door opening shifter, contacts in the closing circuit, and means for separating said contacts when the door is closed.

14. A door control system comprising a reversing door engine, reversing valves therefor, fluid operated valve shifters provided with cylinders of different powers, the stronger cylinders controlling the door opening shifter, electro-magnetically operated valves controlling the respective cylinders,

manual switches for the circuits of said magnets, and an emergency device controlling the circuit to the valve which controls the door opening shifter.

5. 15. A door-control system comprising opposing fluid-pressure cylinders of different power, the weaker for door closing the stronger for door opening, manually-oper-

ated contacts controlling the weaker cylinder to close the door, and emergency means for applying pressures in both cylinders simultaneously to open the door. 10

Signed at New York city, county of New York and State of New York, this 9th day of September, 1920.

GEORGE E. OAKLEY.
